UNITED STATES PATENT OFFICE.

OSCAR A. GARLAND, OF HOT SPRINGS, ARKANSAS.

TALKING DOLL.

Application filed August 27, 1925. Serial No. 52,866.

This invention relates to what are known as talking dolls, that is, dolls and puppet-like toys having means therein whereby the toy may be caused to utter certain words or 5 phrases.

One of the objects of the invention is to provide a toy of this character preferably in the form of a doll having therein a phonographic diaphragm, and button operated 10 means whereby a short record may be brought into engagement with the diaphragm and caused to move with relation to the stylus thereof to thereby cause the utterance of a certain word or sound.

15 A further object is to provide a doll with a plurality of records and a plurality of corresponding buttons so arranged that any one of these buttons when pressed will cause the corresponding record to move across and in 20 contact with the stylus of the diaphragm and cause the utterance of the corresponding sentence or sound.

25 A still further object is to provide a mechanism of this character embodying a diaphragm having a stylus and a longitudinally elongated record formed with a V-shaped groove and mounted upon an arm, and means whereby as the corresponding button is pressed the arm is caused to oscillate, carrying the record into engagement 30 and traversing it with relation to the stylus, means being provided whereby upon a release of said button the arm will reverse its movement and come to its initial position, the stylus being caused to lift prior to the 35 return of the arm so that no sound will be produced.

40 Other objects will appear in the course of the following description.

45 My invention is illustrated in the accompanying drawings, wherein:—

Figure 1 is a perspective view of the phonographic talking apparatus showing the doll in dotted lines;

Figure 2 is an enlarged perspective view of the mechanism shown in Figure 1 but illustrating only one record carrier;

Figure 3 is a fragmentary perspective view of one of the records and its holder;

Figure 4 is a sectional view from front to rear of the lower portion of the mechanism;

Figure 5 is a like view to Figure 4 but showing the parts in the position before a record is moved across the stylus;

55 Referring to Figure 1, wherein is shown a device embodying one of my word or sound

producing mechanisms, 10 designates the rim of a diaphragm 11 and this diaphragm carrying a stylus 12. This ring 10 is supported by two or more springs 13 extending 60 radially from the ring 10 and supported within the doll or other object in any suitable manner so that the springs act to lift the diaphragm and yieldingly resist its downward movement. The ring 10 is formed with a downwardly extending, U-shaped yoke 14 having a cross bar 15 at its lower end.

Mounted adjacent to the cross bar 15 is a shaft 16 upon which is loosely mounted a 70 bell crank lever 17, this bell crank lever being formed with an outwardly projecting, resilient arm 18 having the form of a leaf spring, for instance, which will bear upon the cross bar 15. The opposite arm of the 75 bell crank lever 17 extends upwardly and is connected to a push rod 19 having a button 20 at its extremity. A spring 21 acts to pull the upper arm of the bell crank lever 17 outward and thus project the button 20. The 80 arm 18 also carries upon it a laterally projecting pin 17a.

Loosely mounted upon the shaft 16 for movement independent of the bell crank lever 17 is a record carrying arm 22 which 85 at its upper end carries the longitudinally extended, relatively narrow and somewhat curved record 23. This record has a phonographic groove 24 formed in its upper face, the bottom of this groove being formed with 90 a "Hill and Dale" phonographic record groove. The arm 22 extends down below the shaft 16, as at 25, and is there connected to a flexible element 26 which may be a flexible wire which extends beneath a pulley 27 95 mounted upon an arm 28, in turn attached to the shaft 16 but held with the shaft against rotative movement and in a depending position, and from this pulley the flexible element 26 passes to the cross bar 15 to 100 which it is attached.

The operation of this device so far as described is as follows: Upon an inward pressure exerted upon the button 20, the bell crank lever 17 will be shifted so as to cause 105 the resilient arm 18 to move the yoke 14 with the diaphragm ring 10 downwardly. This will move downward until the springs 13 are tensioned sufficiently to prevent any further movement of the diaphragm ring. 110 At the time this occurs, the pin 17a will bear against the arm 22 and a further movement

inward of the button 20 will cause no further downward movement of the diaphragm but an inward movement of the record 23, causing the record 23 to traverse the stylus 12 and thus to vibrate the diaphragm 11 and thus cause the utterance of the sound which the doll is supposed to make. Upon a release of the button 20, the spring 21 will act to retract the upwardly projecting arm 10 of the bell crank lever and the diaphragm and stylus then rise from the record 23 sufficiently to clear the record before the slack is taken up on the flexible wire 26. The record 23 and the lever 22 are the last to return to their original position. This is secured by the pull of the springs 13 which lift upward on the yoke and the flexible cord 26 then pulls the arm 22 back to its initial position.

While I have heretofore referred to and 20 described a single record and record operating means, I provide also a plurality of records all operating in conjunction with a single diaphragm and stylus and each having an operating means as, for instance, a button 25 whereby any one of these records may be shifted as desired into engagement with the stylus of the diaphragm. Thus I have illustrated for this purpose a plurality of shafts 16 arranged each at right angles to a radial 30 plane drawn through the center of the diaphragm and through the stylus, and I mount upon each one of these shafts the operating mechanism heretofore described. There are thus a plurality of records 23 and a plurality 35 of buttons 20 and, of course, a plurality of flexible connections 26 extending to the cross bar of the yoke 14. With this construction, it is obvious that when any one of the buttons 20 is pressed, a corresponding record 40 will be actuated. These records will be designed to utter various phrases such as "mama," "papa," "baby," etc.

Preferably the phonographic record will 45 be made of the fibrous material from which ordinary disk phonographic records are made and preferably the record itself will be detachable from the arm 22 and held in place by ordinary screws or set screws. The 50 push buttons 20 are located preferably at the waist of the doll and preferably at the back of the doll and the diaphragm is preferably located between the shoulders of the doll.

55 While I have illustrated a mechanism which I believe to be particularly effective for the purpose intended, I do not wish to be limited to this as it is obvious that the construction might be changed in various 60 ways without departing from the spirit of the invention as defined in the appended claims.

I claim:—

65 1. In a toy, a phonographic diaphragm having a stylus, a phonographic record, manually operable means for shifting the

phonographic record into contact with and across said stylus to thereby affect the diaphragm, means acting to retract the record to its initial position, and means causing the diaphragm to lift prior to the return of 70 the record.

2. In a toy, a phonographic diaphragm having a stylus, means for yieldingly supporting the diaphragm against downward movement, a phonographic record mounted for movement diametrically across the diaphragm, means yieldingly urging the record to an initial position to one side of said stylus, and manually operable means for depressing the diaphragm and shifting the 80 phonographic record across the stylus and in contact therewith to thereby vibrate the diaphragm.

3. In a figure toy, a phonographic diaphragm having a stylus, a plurality of 85 phonographic records coacting with the stylus, and manually operable means for shifting any of said records into contact and over said stylus to thereby affect the diaphragm including buttons disposed upon the 90 exterior of the figure toy.

4. In a figure toy, a phonographic diaphragm, springs supporting the same, the diaphragm carrying a downwardly extending U-shaped yoke embodying a cross bar, 95 a yieldable member resting upon the cross bar, manually operable means for shifting said yielding member to depress the cross bar against the action of said springs, a record supporting arm mounted for pivotal movement to carry the record into contact with the stylus and across the stylus, means connected to the yoke whereby as the yoke rises to retract said arm, and means connected to the yoke-operating means to shift the arm inwardly into engagement with the stylus.

5. A figure toy having therein a diaphragm and a mounting therefor, resilient means urging the diaphragm and mounting upwardly, a yoke carried by the diaphragm mounting and depending therefrom and having a cross bar, a bell crank lever mounted at right angles to the cross bar and having a resilient arm yieldingly engaging on top of the cross bar, a push button connected to the other arm of the bell crank lever, the last named arm of the bell crank lever having a laterally projecting finger, a phonographic record, an arm supporting the same and pivotally mounted upon the same axis as the bell crank lever and extending beyond said axis, a spring urging the bell crank lever rearwardly, a flexible connection attached to the lower end of said record carrying arm and to the cross bar, and a pulley beneath which the flexible connection passes.

6. In a figure toy, a diaphragm having a stylus, an elongated member having a V-shaped phonographic track, manually oper-

able means for shifting the phonographic track into contact and across the stylus to thereby affect the diaphragm, and means for retracting the record to its initial position without affecting the diaphragm.

7. In a figure toy, a single diaphragm, a mounting therefor, a stylus on the diaphragm, a plurality of phonographic records movable in planes radial to the stylus, sepa-

rate manually-operable means for selectively shifting said records into contact and across the stylus to thereby affect the stylus, and means for returning the phonographic records to their original position without affecting the diaphragm.

In testimony whereof I hereunto affix my signature.

OSCAR A. GARLAND.
